UNITED STATES PATENT OFFICE.

RALPH V. SAGE, OF WESTMONT BOROUGH, PENNSYLVANIA.

CAR-DOOR SPREADER.

1,077,561.

Specification of Letters Patent.

Patented Nov. 4, 1913.

Application filed June 7, 1913. Serial No. 772,233.

To all whom it may concern:

Be it known that I, RALPH V. SAGE, a citizen of the United States, residing in the borough of Westmont, in the county of Cambria and State of Pennsylvania, have invented certain new and useful Improvements in Car-Door Spreaders; and I do hereby declare the following to be a full, clear, and exact description of the invention, such as will enable others skilled in the art to which it appertains to make and use the same.

My invention relates to improvements in railway car construction and more especially to the door operating mechanism thereof.

The object of my invention is to provide a spreader-bar adapted to connect two or more swinging doors together and to the operating mechanism thereof, and to give to such bar a special form which will have great strength and rigidity relative to the amount of metal thereof.

My invention is particularly adapted for use with hopper bottom cars, either of the regular hopper type, or of the hopper bottom gondola type in which the doors extend below the center sills of the car on each side thereof and are connected together in pairs by means of a spreader-bar, the ends of which are secured to the doors on each side of the center sills; the central portion of said spreader-bar being adapted to pass under the center sills of the car, at which point a link or other connection to the door operating mechanism is secured.

Where a flange extends around the outer edge of the car door, which is usually the case, it is preferable to arch or offset the central portion of the spreader-bar so the said flanges of the door remain whole and not cut away, thereby preserving its strength and stiffness.

Heretofore spreader-bars have been constructed either of a sheet of metal pressed into the regular form, or of a rolled bar of beam or channel cross section cut into suitable lengths with their central portions struck up so as to clear the flanges of the doors. These kinds of spreader-bars have not been found to be altogether satisfactory, either on account of their not being sufficiently rigid, and consequently liable to become twisted, or on account of the fact that their construction is such that they cannot be provided with proper attachments to, and

bracing facilities for, the door, and my invention is designed to obviate these difficulties.

I construct my spreader-bar of cast metal of substantially U-shape in cross section, the bar being arched or offset at its center to thereby pass or clear the flanges of each door, and I make my spreader-bar of the fish-bellied type,—that is, of greater depth at its center and tapering gradually toward each end. The ends of my spreader-bar are attached to the swinging doors, the legs of said spreader-bar extending outwardly therefrom. Integral stiffening brackets project rearwardly from the spreader-bar toward the hinged edges of the doors near the inner side of each door and are riveted thereto, thereby forming a rigid connection between the door and the spreader-bar, at the same time bracing these parts together and preventing twisting or distortion of the spreader-bar and the doors. To stiffen the spreader-bar I cast transverse webs integral with the bar connecting the legs at intermediate points and at the ends thereof, and along the longitudinal outer edges, the ends of the legs of the bar are thickened or flanged, which flanges may extend the entire length of the bar, or nearly to the ends of the bar, as shown in the drawings. The central part of the spreader-bar is formed as a substantially box-shaped structure with a perforation in its top and bottom wall, whereby an eye bolt, or other connection, may be secured, to which a link or other attachment to the door operating mechanism may be made.

The construction of a spreader-bar of cast metal in accordance with my invention enables me to distribute the metal to the best possible advantage, to meet the stresses to which it is subjected, and the bar is of great strength and rigidity, and one which can be easily attached to the doors. The integral bracket flange connection, near the inner edge of each door, forms a reinforcement at the weakest point of attachment and also braces the door while the central perforated box-shaped structure provides an easy means for attachment thereto of the link or other connection from the door operating mechanism.

Having thus given a general description of my invention, I will now, in order to make the same more clear, refer to the ac-

companying one sheet of drawings forming part of this specification, in which:

Figure 1 is a vertical longitudinal sectional elevation on an enlarged scale taken on the line I—I of Fig. 2, through the lower hopper portion of a car showing a pair of oppositely swinging doors in closed position, and my spreader-bar in section, attached to the forward edge of each, and also showing enough of the adjoining car structure to clearly illustrate the application of my invention. Fig. 2 is a vertical transverse sectional elevation taken on the line II—II of Fig. 1, showing the lower portion of a car, the hoppers of which extend downwardly on each side of the center sills, and a pair of similar swinging doors adapted to close the bottom thereof, together with my improved spreader-bar connecting and supporting the doors in cooperation with the door operating mechanism. Fig. 3 is a detached top plan view of my improved spreader-bar; Fig. 4 is a side elevation thereof, and Fig. 5 is a bottom plan view of the spreader-bar. Fig. 6 is a vertical transverse sectional elevation of the spreader-bar taken on the line VI—VI of Fig. 4 through the central box-shaped portion of the bar, and Fig. 7 is a vertical transverse sectional elevation taken on the line VII—VII of Fig. 4 looking in the direction of the arrows.

Referring now to the numbers of reference on the drawings:—1 indicates the center sills of the car and 2 the sides thereof. Hopper sheets 3 are attached to, and extend downwardly below, the bottom edges of the car sides, and also extend below the center sills of the car, while the doors 4 are hinged at 5 to the bottom edges of the hopper mouths and form the closures for the same.

To complete the illustration, two hoppers are shown on the drawings, each hopper having a pair of swinging doors connected together by my improved spreader-bar 6, although it will be understood that the doors may be differently disposed, either transversely or longitudinally of the car, without departing from the spirit of my invention.

My spreader-bar 6 is substantially U-shaped in cross-section, the legs thereof being of greater depth in the central portion, while the bar is arched or offset as at 7 and tapers gradually, or becomes shallower, toward each end. The legs and top of the bar are connected together centrally, intermediately and at the ends by transverse webs 8, 9, and 10 respectively, the lower face of the bar being otherwise open, with the exception of a nut bearing surface 11, which connects the central webs 8 and the ends of the U-shaped legs together and

forms a substantially rectangular box-shaped structure at this point.

Perforations extend through the nut bearing surface 11, as at 12, and also through the top offset portion of the bar as at 13, with lateral stiffening flanges 14 of segmental outline extending from either side of the face of the bar at this point, for the purpose of reinforcing the same and forming a better bearing for the head of the eye bolt 15. Along the ends of the legs of the bar on the outside thereof is a thickening or flange 16 which extends nearly to the ends of the bar.

The upper surfaces 17 of the tapered ends of the spreader-bar are flat and perforated in various places, as shown at 18, and form the surfaces which bear against the car doors on the outside thereof. Reinforcing brackets 19, having perforated bearing surfaces, extend from one side of, and on the same plane as, the upper surfaces 17, and are similarly perforated as at 20. These brackets 19 extend rearwardly and are attached to the doors near the inner side edges thereof and by means of this construction, each door is braced both longitudinally and transversely.

The central perforated box-shaped construction affords a good bearing for attaching the eye bolt 15, to which is pivoted a link 21 of the door operating mechanism, which may be of any type adapted for this purpose and is consequently not shown.

My spreader-bar is so constructed as to enable it to be used on either pair of doors by simply turning it end for end, as will be clearly understood by referring to the drawings.

While I have shown and described my invention in considerable detail, I do not wish to be limited to the exact construction specified, but may use such substitutions, modifications or equivalents thereof, as are embraced within the scope of my invention, as pointed out in the claims.

Having thus described my invention, what I claim and desire to secure by Letters-Patent is:—

1. In a dumping car, a pair of hinged doors thereon, a cast spreader-bar substantially U-shaped in cross section, secured to, and connecting said pair of doors, the legs of said U-shaped bar being connected together at intervals by webs formed integral therewith.

2. In a dumping car, a plurality of hinged doors thereon, a cast spreader-bar substantially U-shaped in cross section, secured to, and connecting said hinged doors, said U-shaped bar being of greatest depth centrally and tapering gradually toward each end, and provided with integral webs connecting the legs of said U-shaped bar.

3. In dumping car, a plurality of hinged doors thereon, a spreader-bar substantially U-shaped in cross section, secured to, and connecting said plurality of doors, integral webs connecting the legs of the U-shaped bar, said bar having an arched or offset central portion and tapering end portions. 5 to, and connecting said doors, integral webs 55 connecting the legs of the central portion of the bar, the central portion of the ends of the legs and the ends of the adjacent webs being connected integrally, forming a nut bearing surface. 60
4. In a dumping car, a plurality of hinged doors thereon, a spreader-bar substantially U-shaped in cross section, integral web connections between the legs of the U-shaped bar, said spreader-bar having an offset central portion and tapering end portions, the upper faces of said tapering end portions 10 being flat and connected to said doors. 65
5. In a dumping car, a plurality of alined hinged doors thereon, a spreader-bar substantially U-shaped in cross section, transverse web connections between the legs of the U-shaped bar, said U-shaped bar having an offset central portion and tapering end portions, the upper face of said tapering end portions being straight, perforations in the straight faces of the end portions and a perforated integral bracket extending laterally 15 from said end portions, whereby said bar is 70 connected to said doors. 75
6. In a dumping car, a plurality of alined hinged doors thereon, a spreader-bar substantially U-shaped in cross section, secured to, and connecting said hinged doors, transverse web connections between the legs of the U-shaped bar, said bar having an offset central portion and tapering end portions, the edges of the legs of 20 said U-shaped bar being thickened or flanged. 80
7. In a dumping car, a plurality of alined hinged doors thereon, a spreader-bar substantially U-shaped in cross section, integral flanges extending from the edges of the legs of said U-shaped bar, transverse web connections between the legs thereof, said bar having an offset central portion and tapering end portions, the upper faces of the tapering end portions being plane and perforated, a perforated integral bracket 25 extending laterally from each of said end portions, and means for securing the spreader-bar to said doors through the said perforations. 85
8. In a dumping car, a plurality of alined doors hinged thereon, a spreader-bar substantially U-shaped in cross section, secured 30

to, and connecting said doors, integral webs 55 connecting the legs of the central portion of the bar, the central portion of the ends of the legs and the ends of the adjacent webs being connected integrally, forming a nut bearing surface. 60

9. In a dumping car, a plurality of alined doors hinged thereon, a spreader-bar substantially U-shaped in cross section, secured to, and connecting said doors, transverse webs connecting the legs thereof adjacent to 65 the central portion of the bar, the ends of the legs of the U-shaped bar and the ends of the adjacent webs being integrally connected, thus forming a nut bearing surface, a perforation in the nut bearing surface and 70 in the top surface of the bar in vertical alinement, and lateral curved flanges extending from the top of the bar on either side of the perforation. 75

10. In a dumping car, a plurality of alined hinged doors thereon, a spreader-bar substantially U-shaped in cross section, integral flanges extending from the outer edges of the legs of said U-shaped bar, transverse webs connecting the legs of the U-shaped bar centrally, the central portion of the edges of the legs of the bar and the edges of the adjacent central transverse webs being connected integrally, thereby forming a nut bearing surface, said bar having an offset 80 central portion and tapering end portions, the upper faces of the tapering end portions being plane, perforations in the plane faces of the end portions, and a perforated bracket extending laterally from each of said end 85 portions, its upper face being in the same plane therewith, and means for connecting said bar to the doors through said perforations. 90

11. A one-piece cast spreader-bar of approximately U-section, with flanges extending laterally in a plane from the end portions thereof, brackets forming extensions of said flanges, the central portion of said bar being offset and provided with means for attachment to the operating mechanism. 95

In testimony whereof I hereto affix my signature in the presence of two witnesses.
